(57) **CLAIM**

The ornamental design for the snow blower light, as shown and described.

DESCRIPTION

FIG. 1 is a perspective view embodying the design of a snow blower light of the present invention;

FIG. 2 is a front view of the snow blower light;

FIG. 3 is a side view of the snow blower light; and,

FIG. 4 is a top view of the snow blower light.

The broken line showing of the snow blower is included for the purpose of illustrating only and forms no part of the claimed design.

CERTIFICATE OF CORRECTION

PATENT NO. : D672,072 S
APPLICATION NO. : 29/387816
DATED : December 4, 2012
INVENTOR(S) : Joseph Cohen

Page 1 of 4

It is certified that error appears in the above-identified patent and that said Letters Patent is hereby corrected as shown below:

Title Page, illustrative fig. 1 should be deleted and substitute therefor the attached title page consisting of the illustrative fig. 1.

In the Drawings

The drawing sheets 1 and 2 should be deleted and substitute therefor the attached drawing sheets consisting of figs. 1-4.

Signed and Sealed this
Eighth Day of October, 2013

Teresa Stanek Rea
Deputy Director of the United States Patent and Trademark Office
